CLAIM

The ornamental design for a corner bead roller tool, as shown and described.

DESCRIPTION

FIG. 1 is a side perspective view of an embodiment of the present corner bead roller tool;

FIG. 2 is a side view of the corner bead roller tool of FIG. 1, both sides being identical;

FIG. 3 is a front view of the same;

FIG. 4 is a rear view of the same;

FIG. 5 is a top view of the same; and,

FIG. 6 is a bottom view of the same.

The structures depicted in broken lines are provided for environment purposes only and do not constitute part of the claimed invention.
